A. HILLMAN, OF DEVONSHIRE, ENGLAND, ASSIGNOR TO THOMAS R. FULLER,
SAMUEL S. FULLER, AND JAMES S. McMURRAY.

Letters Patent No. 72,200, dated December 17, 1867.

CAR-COUPING.

The Schedule referred to in these Letters Patent and making part of the same.

TO ALL WHOM IT MAY CONCERN:

Be it known that I, A. HILLMAN, of Davenport, in the county of Devonshire, England, have invented a new and useful Improvement in Car-Coupling; and I do hereby declare that the following is a full, clear, and exact description thereof, which will enable those skilled in the art to make and use the same, reference being had to the accompanying drawings, forming part of this specification, in which—

Figure 1 is a vertical longitudinal section of my improved car-coupling, attached to cars.

Figure 2 is a detail sectional view of the same, taken through the line x x , fig. 1.

Similar letters of reference indicate corresponding parts.

My invention has for its object to furnish an improved car-coupling, simple, strong, and reliable in construction, not liable to get out of order, which shall be self-coupling, and which may be readily attached to an ordinary draw-bar and bumper-head; and it consists in the coupling-box; in the coupling-link having two pins projecting downward; in forming holes or slots in the lower part of the coupling-box for the reception of the link-pins; in the combination of the slotted wedge-shaped adjusting-block with the coupling-link, and in the combination and arrangement of the coupling-box, spring, pivoted coupling-bar, uncoupling-rod, and lever-handles with each other; the whole being constructed and arranged as hereinafter more fully described.

A and B are the contiguous ends of two cars coupled with my improved coupling. C are the ordinary draught-bars and bumper-heads, which are attached to the cars in the ordinary manner. D are the boxes of the coupling, upon the upper side of which is formed a flange, d^1 , fitting over one or both the draught-bars C, to which the box is secured by bolts passing through the said flange, through the draught-bar or bars, and through the upper side of the said box, the said bolts being secured in place by nuts, keys, or in any other convenient manner. E are braces, the lower ends of which are securely bolted to the sides of the coupling-box D, and their upper ends to the draught-bar, so as to hold the said boxes D securely in place. The connection between the draught-bars C and the coupling-boxes D may be still further strengthened by the ordinary coupling-pins F, which pass down through the upper part of the boxes D, as shown in fig. 1. G are the coupling-bars, the upper ends of which are pivoted to ears or projections d^2 , formed upon or attached to the rear side of the boxes D, by means of the uncoupling-shaft or rod H, to which they are securely attached, and which pass through the said ears or projections d^2 . To the outer ends of the uncoupling-rod H are attached lever-handles I, by means of which the cars may be uncoupled from the side of the track or from the platform of the station; or, if desired, a cord may be attached to the lever-handles I and carried up to the top or other desired part of the car, for convenience in uncoupling. The coupling-bars G are made with a shoulder upon the rear side of their lower ends to rest upon the end of the coupling-link, and hold it in a horizontal position, ready for coupling the cars when they are run together. J is a spring, which is secured to the coupling-bar G or to the uncoupling-rod H in such a position that its free end will rest or strike against the draught-bar C and prevent the said coupling-bars G from being thrown out of the coupling-link by the jarring of the cars. The spring J also insures the coupling-bars being always in position to drop into the link and couple the cars when they are run together. The lower sides of the boxes D are made inclined, so as to guide the coupling-link into proper position for coupling, and have two holes or slots formed in them to receive the pins attached to the coupling-link, to prevent the said link from being driven into the box D when the cars are run together to be coupled. K is the coupling-link, the rear end of which has a notch formed in it, into which the lower end of the coupling-bar G fits, and two pins, k' , attached to its lower side, which enter the holes or slots in the lower side of the boxes D, and which prevent the link K from being driven too far into the said boxes when the cars are run together to be coupled. L is a wedge-shaped block, which is secured to the rear end of the link K by a bolt and thumb-nut, said bolt passing through a hole in the rear end of the said link, and through a slot in the said block. The block L is secured to the end of the link K in such a position that it may pass beneath and rest against the shoulder formed upon the lower part of the bar G, so that it may be adjusted to hold the link in a horizontal position, should the draught-bar be accidentally bent downward, or be otherwise thrown out of a horizontal position. In the case of high cars the boxes may be made deeper, so as to bring high and low cars practically to the same level; or the links K may be bent in the same way as is now done to couple high and low cars.

By this construction, the ordinary bumper-heads not being removed, the old coupling is not disturbed, so that a car without my improved coupling can be readily coupled with one to which my improved coupling has been attached. In case the draw-bars C are slotted in the rear of the pin F, the projections d^2 of the box D may be placed above the said draw-bar, allowing the coupling-bar G and spring J to work up and down through said slot. In this case, if desired, the spring J may be secured to the draw-bar C, so as to act upon the head of the coupling-bar G.

I claim as new, and desire to secure by Letters Patent—

1. The coupling-boxes D, constructed as described, and secured to the draught-bar or bars C by the flange d^1 and braces E, substantially as and for the purpose herein set forth.
2. The coupling-link K, constructed as herein shown and described, and having two downwardly-projecting pins k' attached to its lower side, in combination with the coupling-box, having perforations for the reception of the pins k' of the link K, substantially as and for the purpose herein set forth.
3. The combination of the slotted wedge-shaped adjusting-block L with the coupling-link K, substantially as herein shown and described, and for the purpose set forth.
4. The combination and arrangement of the coupling-box D, spring J, pivoted coupling-bar G, uncoupling-rod H, and lever-handles I with each other and with the draught-bar C, substantially as herein shown and described, and for the purpose set forth.

A. HILLMAN.
